UNITED STATES PATENT OFFICE.

ANTHONY L. HERKENHOFF, OF MINSTER, OHIO, ASSIGNOR TO THE
MINSTER MACHINE COMPANY, A COMPANY EXISTING UNDER THE
LAW OF OHIO.

FRICITION-CLUTCH.

SPECIFICATION forming part of Letters Patent No. 795,037, dated July 18, 1905.

Application filed March 18, 1904. Serial No. 198,844.

To all whom it may concern:

Be it known that I, ANTHONY L. HERKENHOFF, a citizen of the United States, residing at Minster, in the county of Auglaize and State of Ohio, have invented certain new and useful Improvements in Friction-Clutches, of which the following is a specification, reference being had therein to the accompanying drawings.

10 My invention relates to certain new and useful improvements in friction-clutches, hereinafter set forth, and particularly pointed out in the claims.

15 The object of this invention is to provide inner and outer friction expansion-rings, which will be composed of two independent and opposing balanced sections, one section comprising alternate inner and outer poised segments and the other section comprising

20 similar alternate inner and outer poised segments, the inner segment of the one section being opposed to the outer segment of the other section, and both of which segments are independent of each other, so that the 25 frictional contact of the inner and outer friction-rings with the friction-surfaces of the clutch-pulley will be readily obtained by expanding or separating said independent and opposing segments; also, to construct the

30 friction-ring segments so that the inner segment will counterbalance the outer segment of each section, whereby the centrifugal force of said segments of the friction-rings will be counteracted to prevent said friction-rings 35 contacting with the friction-surfaces of the said clutch-pulley when released, thereby promptly releasing the said pulley when said friction-rings are not required to operate to engage the said pulley. I attain these ob-

40 jects by means of the mechanism illustrated in the accompanying drawings, in which similar numerals of reference designate like parts throughout the several views.

Figure 1 is an end elevation of the clutch-pulley looking in the direction of the arrow *a*. (See Fig. 2.) Fig. 2 is a transverse sectional elevation of the clutch-pulley, taken through the line A B. (See Fig. 1.) Fig. 3 is a detail view of the expansion friction-ring, showing

the position of the opposing sections thereof. 50 Fig. 4 is a part transverse sectional view of the same, taken through the line *a b*. Fig. 5 is a detail view of the lever-carrier. Fig. 6 is a detail view of one of the sections of the friction-rings, and Fig. 7 is a detail perspective 55 view of the friction-ring-clutch-operating lever.

The pulley 1 has its hub 2 truly bored to turn on the sleeve 3 between the collar 4 thereof and the clutch-lever carrier 5, by and 60 between which collar 4 and lever-carrier 5 said pulley is retained in position on said sleeve. The sleeve 3 is secured on the shaft 6 to turn therewith by means of a set-screw 7 or other suitable means, as a key, and the 65 clutch-lever carrier 5 is also secured to said shaft to turn therewith by a key or set-screw, or both.

The end of the hub 2 between the web 8 of the pulley 1 and the clutch-lever carrier 5 is 70 turned on its peripheral surface to be concentric with the axis of rotation of the pulley, and consequently with the periphery of the said hub 2, and intermediate between the hub 2 and the rim of the pulley 1 is formed 75 integral therewith the friction-flange 9, and the same is truly turned on its inner peripheral surface to have its surface equally distant from the peripheral surface of the hub 2. The friction clutch-ring is composed of two 80 opposing sections, each of which comprises an inner segment 10 and an outer segment 11, and each of said alternate inner and outer segments is connected at one of its ends to, or is constructed to form a single integral piece 85 with, the connecting-block 12, and each of said inner and outer segments 10 and 11 is of equal weight, so that the centrifugal force of the inner segment 10 will counterbalance that of the outer segment 11, and the said 90 block 12 of said segment is drilled to receive their pivotal retaining-pins 13, upon which said friction-ring sections are mounted, and the said pivotal pins 13 are screwed in the bore of the lugs 14, formed integral on the 95 clutch-lever carrier 5 by its retaining-nut 15, so that the inner segments 10 are free to be forced against the peripheral surface of the

hub 2, and the outer segments 11 are forced outwardly against the inner peripheral surface of the friction-flange 9, and each of the opposing sections constituting the friction-ring is free to operate simultaneously and independently of the other. The driving force of the shaft 6 or the pulley 1, as the case may be, is transmitted directly from the friction-segments 10 and 11 to said pivotal pins 13, and the expanding clutch-levers 16 are released of all transverse stress, which would tend to bend or distort them and render them inoperative. The expanding clutch-levers 16 of the friction-clutch segments 10 and 11 are disposed at equal distances apart from the center of the sleeve 5 at diametrically opposing sides thereof, and the same are adapted to freely work between the guide-lugs 17, formed integral on the said clutch-lever carrier 5. The guide-lugs 17 are provided with the guide-slots 18, in which latter the guide-pins 19 of the levers 16 freely work, and the said pins are provided for the purpose of retaining the said levers in position and preventing them from moving longitudinally. The clutch-levers 16 are provided with the rounded bearing portions or toes 20 and 21, which project slightly above the bottom and top edges of the said levers, and said toes are so situated relatively to each other that when the free ends of the said levers 16 are moved outwardly said toes will bear against said opposing friction-segments 10 and 11 to separate them and force them against the friction contact-surfaces of the pulley 1—namely, the flange 9 and the hub 2. The lines connecting the centers of the opposing toes 20 and 21 are at an angle with the longitudinal axis of the levers 16, and the said lines form the short lever-arms of the said clutch-levers. Toes or engaging pins 20^a and 21^a are situated on said levers centrally with the toes 20 and 21, and the same project from each side of said clutch-levers 16 for the purpose of engaging the retaining-lips 10^a and 11^a, formed integral on the lugs 10^b and 11^b of the friction-segments 10 and 11. This construction is provided for the purpose of positively moving said friction-segments 10 and 11 from the friction-clutch surfaces of the pulley 1 to release the latter and retain said friction-segments in released position.

55 The free or outer ends of the levers 16 are cranked or offset outwardly to provide suitable clearance or space for the proper working of the toggle-links 22.

60 A traversing sleeve 23 is mounted on the shaft 6 to turn therewith and to be traversed longitudinally thereon, and the said sleeve is provided with the lugs 24, which are pivoted to the ends of the adjustable end members 25 of the toggle-links 22. The toggle-links 22 are provided with the eyebolt end members

25, which have their threaded ends screwed in the ends of the toggles 22, which end members 25 are pivotally connected to the lugs 24 of the traversing sleeve 23, and the said construction is provided for the purpose of varying and adjusting the lengths of the toggles as the friction-segments 10 and 11 are worn and need "take-up." Lock-nuts 26 are also provided for locking the said end members 25 of the toggles 22 and preventing the eyebolts or end members 25 from working loose. The traversing sleeve 23 may be traversed on said shaft 6 either while the latter is in motion or at rest to either relieve the said friction-segments or engage the same through 80 and by means of any suitable operating clutch-lever the construction of which is well known and needs no description.

It is obvious that it is immaterial whether the shaft 6 or the pulley 1 be the driver, as 85 the mechanism is operative under either condition of power transmission.

When it is required to release the friction-segments 10 and 11 or move them out of contact with the friction-surfaces of the hub 2 and the flange 9, the sleeve 23 is traversed on the shaft 6 in the direction of the arrow *a* to cause the free ends of the clutch-levers 16 to approach radially near the said shaft, thereby releasing the contacting toes 20 and 21 of said levers from contact with the friction-segments 10 and 11, which segments are operated to positively recede by the pins or toes 20^a and 21^a, and said friction-segments are positively held in said released normal position and out of contact with the friction-surfaces of the hub 2 and the flange 9 by said pins 20^a and 21^a, thereby permitting the free rotation of the pulley on the shaft 6. It is obvious that when it is necessary to cause the friction or clutch segments 10 and 11 to engage or bind their opposing surfaces or the surfaces of the hub 2 and the flange 9 to cause the pulley 1 to turn with the shaft 6 the traversing sleeve 23 is traversed on said shaft in the direction opposed to that indicated by the arrow *a* till it reaches the position shown in Fig. 2, in which position the bearing-toes 20 and 21 of the levers 16 operate to expand or separate said segments 10 and 11 to bind them between said surfaces of the hub 2 and the flange 9 to cause said pulley 1 to rotate with said shaft 6. In order that the frictional resistance between the bearing-surfaces of the ring members 10 and 11 and the friction-surfaces of the hub 2 and the flange 9 of the clutch-pulley 23 be increased to the maximum, I provide a thin layer or sheathing of friction-producing material, as 27, preferably fiber-sheeting, which is first cut to the proper size and firmly secured to each of the surfaces of the ring members 10 and 11 and the surfaces of the hub 2 and the flange 9 by suitable rivets or other fastenings which have their heads countersunk into said fiber covering 130

to present a smooth even surface of contact. Another important feature of this invention to be particularly noted is the manner of neutralizing the centrifugal force exerted by the 5 ends of the clutch-levers 16 and applied to the opposing balanced segments 10 and 11. The toe or pin 20^a of the clutch-lever 16 engages the lips 10^a of the inner section 10 of the friction-ring on one side of the hub 2 of the 10 pulley, and the toe or pin 21^a similarly engages the lip 11^a of the outer segment 11 on the same side of the hub. Similarly, the toe or pin 20^a of the opposing clutch-lever 16 engages the lip 10^a of the inner opposing segment 15 10 of the friction-ring on the opposite side of the hub 2 of the pulley, and the toe or pin 21^a similarly engages the lip 11^a of the outer segment 11 on this side of the hub 2, and thus while the centrifugal force exerted 20 by the end of one of the clutch-levers 16 is applied to the lips 10^a to force the segment 10 outwardly the centrifugal force exerted by the end of the opposing clutch-lever 16 is applied to the bearing situated between the 25 lips 11^a to force the segment 11 outwardly, and thus two diametrically opposing forces are applied to the segments 10 and 11 of the same section which balance, and the opposing inner and outer sections are at all times 30 maintained in equilibrium.

Having thus fully described this my invention, what I claim as new and useful, and desire to cover by Letters Patent of the United States therefor, is—

35 1. In a clutch-pulley, the combination with a shaft, a pulley adapted to turn on said shaft, a hub on said pulley and a rim concentric with said hub, of a friction or clutch ring composed of a pair of inner and outer opposing balanced sections, said sections situated between the rim and the hub of said pulley, means for separating or spreading apart said friction or clutch ring sections to engage said pulley, means fixed on said shaft 40 for pivotally supporting said opposing sections at their centers of gravity, and independent supporting means whereto the separating or spreading means are secured to rotate with said shaft.

50 2. In a clutch-pulley, the combination with a shaft, a pulley adapted to turn on said shaft, a hub on said pulley and a rim concentric with said hub, of a friction or clutch ring composed of a pair of opposing balanced sections situated between the rim and the hub of said pulley and each section comprising alternate inner and outer segments, means for separating or spreading apart said friction or clutch ring sections to engage said 55 pulley, means fixed on said shaft for pivotally supporting said opposing sections at their centers of gravity, and independent supporting means whereto the separating or spreading means are secured to rotate with said shaft.

3. In a clutch-pulley, the combination with a shaft, a pulley adapted to turn on said shaft, a hub on said pulley and a rim concentric with said hub, of a friction or clutch ring composed of a pair of opposing balanced sections situated between the rim and the hub of said pulley, each opposing section comprising alternate inner and outer balanced segments, levers situated on diametrically opposite sides of said shaft for separating or 70 spreading apart said friction or clutch ring sections to engage said pulley, means for pivotally supporting said opposing sections at their centers of gravity, and independent supporting means whereto the separating or 75 spreading levers are secured to rotate with said shaft.

4. In a clutch-pulley, the combination with a shaft, a pulley adapted to turn on said shaft, a hub on said pulley and a rim concentric with said hub, of a friction or clutch ring composed of a pair of opposing balanced sections situated between the rim and the hub of said pulley, each opposing section comprising alternate inner and outer balanced segments, and each of said sections formed in a single integral piece, means for separating or 85 spreading apart said friction or clutch ring sections to engage said pulley, means for pivotally supporting said opposing sections at 90 their centers of gravity, and independent supporting means whereto the separating or spreading means are secured to rotate with said shaft.

5. In a clutch-pulley, the combination with a shaft, a pulley adapted to turn on said shaft, a hub on said pulley and a rim concentric with said hub, of a friction or clutch ring composed of a pair of opposing balanced sections situated between the rim and the hub of said pulley, each opposing section comprising alternate inner and outer balanced segments, and each of said sections formed in a single integral piece, levers situated on diametrically opposite sides of said shaft for 100 separating or spreading apart said friction or clutch ring sections to engage the rim and hub of said pulley, means on said shaft for pivotally supporting said balanced segments at their centers of gravity, and independent 105 supporting-levers whereby said separating or spreading levers are carried to rotate with said shaft.

6. In a clutch-pulley, the combination with a shaft, a pulley adapted to turn on said shaft, a hub on said pulley and a rim concentric with said hub, of a friction or clutch ring composed of a pair of opposing balanced sections pivoted at their central portions and situated between the rim and the hub of the 110 pulley, each opposing section comprising alternate inner and outer balanced segments, and each of said sections formed in a single integral piece, means for separating or spreading apart said friction or clutch ring sections 115 120

to engage said pulley, means for pivotally supporting said balanced segments at their centers of gravity, and independent supporting means whereby said separating or spreading means are carried to rotate with said shaft.

7. In a clutch-pulley, the combination with a shaft, a pulley adapted to turn on said shaft, a hub on said pulley and a rim concentric with said hub, of a friction or clutch ring composed of opposing balanced sections pivoted at their central portions and situated between the rim and the hub of the pulley, each opposing section comprising alternate inner and outer balanced segments, and each of said sections formed in a single integral piece, a lever-carrier secured on said shaft to turn therewith, opposing clutch-levers situated on diametrically opposite sides of said shaft and guided by said lever-carrier, said levers having their operative or separating ends situated between the inner and outer segments of said friction-ring sections, and said balanced segments pivotally mounted on said lever-carrier, and means for operating said levers to separate said opposing segments of said friction-ring.

8. In a clutch-pulley, the combination with a shaft, a pulley adapted to turn on said shaft, a hub on said pulley and a rim concentric with said hub, of a friction or clutch ring composed of opposing pivotally-mounted balanced sections situated between the rim and the hub of said pulley, each opposing section comprising alternate inner and outer balanced segments, outwardly-extending engaging lips formed on the peripheral outer surface of said inner segments, inwardly-extending opposing engaging lips formed on the inner peripheral surface of said outer segments, a lever-carrier secured on said shaft to turn therewith, means for pivotally securing said segments at their centers of gravity to said lever-carrier, opposing clutch-levers

situated on diametrically opposite sides of 45 said shaft, said levers having their operative or separating ends situated between the inner and outer segments of said friction-ring sections, engaging pins extending from the sides of the operative ends of said levers and 50 adapted to engage the inwardly and outwardly extending engaging lips of said segments, and means for operating the said levers to expand or separate said friction-ring segments.

9. In a clutch-pulley, the combination with a shaft, a pulley adapted to turn on said shaft, a hub on said pulley and a rim concentric with said hub, of a friction or clutch ring composed of opposing pivotally-mounted 60 balanced sections situated between the rim and the hub of said pulley, each opposing section comprising alternate inner and outer balanced segments, the inner segment of the one opposite to the outer segment of the 65 other, a lever-carrier secured on the said shaft to turn therewith, opposing clutch-levers situated on diametrically opposite sides of said shaft and having their operative or separating ends situated between the inner 70 and outer segments of said friction-ring sections, means for pivotally securing said segments at their centers of gravity to said lever-carrier, means for connecting the operative ends of the said levers to the inner and outer segments of said friction-ring sections 75 so that the centrifugal force of the said levers is divided between and counterbalanced by said inner and outer balanced segments, and means for operating said levers to expand 80 said friction-ring segments.

In testimony whereof I affix my signature in presence of two witnesses.

ANTHONY L. HERKENHOFF.
